[57] CLAIM

The ornamental design for an inhalator, as shown and described.

DESCRIPTION

FIG. 1 is a top perspective view of an inhalator showing our new design, in closed position;

FIG. 2 is a top perspective view thereof, in open position;

FIG. 3 is a top plan view thereof;

FIG. 4 is a right side elevational view, the left side elevational view being a mirror image thereof;

FIG. 5 is a front elevational view thereof;

FIG. 6 is a bottom plan view thereof; and

FIG. 7 is a rear elevational view thereof.
